UNITED STATES PATENT OFFICE.

CLARENCE ERROL FERREE, OF BRYN MAWR, PENNSYLVANIA.

LIGHTING FIXTURE.

Application filed December 9, 1924. Serial No. 754,707.

My invention relates to semi-indirect lighting fixtures and it has for its general object to provide a novel construction of fixture in which simplicity and efficiency 5 are combined in a high degree.

Other objects and advantages of the invention will be pointed out in the detailed description thereof which follows or will be apparent from such description.

10 In order that the invention may be readily understood and its practical advantages fully appreciated reference may be had to the accompanying drawing in which I have illustrated certain convenient forms of embodiment of the same. However, it will be understood that the invention may be embodied in other forms of construction than those shown and that changes in the details of construction may be made within the 15 scope of the claims without departing from the principle thereof.

In the drawing, Fig. 1 is a view in sectional elevation of a fixture embodying the said invention;

20 Fig. 2 is a similar view showing a modified construction of fixture embodying the said invention; and

Fig. 3 is a view in elevation of a modified construction of electric light bulb.

30 Referring to the drawing:—1 designates a bowl-shaped member or shade of translucent material which may be relatively shallow as illustrated. It is provided at its center with an opening 2 through which the lower end portion of the glass bulb 3 of an electric light projects, as indicated. The upper edge of the opening 2 preferably should be surrounded by a raised portion 4 about one-eighth of an inch in thickness 35 or height in order to prevent too high a brightness of the bowl near the lamp. The inner surface of the bowl should have a gradual curve from the center outwardly and upwardly, as illustrated, so as to cause 40 it to receive equal amounts of light from the upper portion of the light source, which comprises an electric light filament 5 within the bulb 3, the intention being to provide a softly luminous bowl of low and even 45 brightness with a minimum loss of light.

50 Depending upon the density of this bowl the fixture can be made either semi-indirect or indirect of the luminous bowl type.

55 The bowl-shaped member or shade 1 is supported by means of chains 10, or other suitable means, only two of which are

shown. The electric light bulb 3 is adapted to be engaged with and disengaged from a socket 11 in known manner which is supported by means of a chain 12 which is 60 suspended from the lower end of a tubular member 13 which is attached to and projects from a ceiling or other structure 14. The upper ends of the chains 10 are likewise connected to the tubular member 13. 65

The convex outer surface of the lower end portion of the bulb 3 is provided with a coating 15 of silver, or other suitable material, which may be applied and secured thereto in any desired known manner. The 70 bulb 3 projects through the opening 2 to such point that the upper edge of the metal coating 15 is substantially flush with the adjacent inside edge of the bowl and consequently occupies a plane below the upper 75 edge of the rim portion 4.

In the construction as shown in Figs. 1 and 2 the upper portion of the glass bulb employed is smooth and transparent so that the light rays which proceed directly 80 from the electric light filament 5 and also those which are reflected from the inner concaved surface of the metal coating 15 pass directly therethrough with little or no diffusion. 85

90 In the construction as illustrated in Fig. 1 no diffusing means is employed and consequently the illumination of the ceiling of a room or other reflecting surface against which the light is directed would not be as uniform or as well diffused as the illumination which would be produced by a structure such as shown in Figs. 2 and 3 of the drawing in which the diffusing means is employed. Moreover in the construction as 95 shown in Fig. 1 shadow images of the electric light filament 5 and the portion of the structure directly associated therewith are likely to be cast on the ceiling or other reflecting surface against which the light is 100 directed.

105 In the construction as shown in Fig. 2 of the drawing a diffusing shield or shade 20 is employed which shield flares outwardly from its upper to its lower end. The said shield is supported upon the socket 11 to and from which the bulb 3 is adapted to be attached and detached. The diffusing shield or shade 20 may consist either of translucent material or of transparent material, a surface of which is lightly etched or provided with a coating 110

of a suitable substance, preferably very thin, to render the same light diffusing. This shield may or may not be tinted blue for the purpose of correcting the light to day-light color.

The lower edge of the shield or shade 20 is located a short distance from the upper surface of the bowl-shaped member 1 while the electric light filament 5 is located a short 10 distance below the upper edge of the metal coating 15 so that all of the light rays which radiate to the ceiling of a room or other surface from the electric light filament 5 or are reflected to the ceiling from the 15 metal coating 15 must pass through the diffusing shield or shade 20; also the greater portion of the light which illuminates the bowl-shaped member must pass through the diffusing shield 20 which insures an even 20 illumination of said bowl-shaped member.

In Fig. 3 an electric light bulb is shown which is identical with the bulb shown in Figs. 1 and 2 except that the outer surface of the portion of the bulb above the upper 25 edge of the metal coating 15 is lightly etched or lightly frosted as indicated at 21. If the bulb shown in Fig. 3 be substituted for the bulb shown in Fig. 2 the shield or shade 20 shown in the latter figure may 30 be dispensed with because the etching or frosting of the outer surface, as indicated at 21, operates to effect diffusion of the light rays from the filament 5.

It will be seen that by my invention I 35 am enabled to obtain great illuminating efficiency by means of a unit of very simple construction which may be operated without loss of efficiency due to the accumulation of dirt or dust on the reflecting surface 40 which is completely inclosed.

Having thus described my invention, what I claim and desire to secure by Letters Patent is:

1. A lighting fixture comprising a bowl-shaped member of translucent material having a central opening therethrough, an electric light bulb provided with a filament which is adapted to be rendered incandescent and also provided upon the outer 45 surface of its lower end portion with a light reflecting coating, the upper edge of which extends a short distance above the said filament, and the said bulb projecting into the said opening to an extent to bring 50 the upper edge of the said coating into substantially flush relation with respect to the adjacent inner surface of the said bowl-shaped member.

2. A lighting fixture comprising a bowl-shaped member of translucent material, which member is provided with a central opening extending therethrough, an electric light bulb having a filament therein which is adapted to be rendered incandescent by 60 the flow of electric current therethrough,

and the outer surface of the lower end portion of said bulb being provided with a metal coating the upper edge of which extends a short distance above the said filament, and means for supporting the said bulb with the lower end portion thereof projecting into the said opening, the upper edge of the said coating being substantially flush with the inner surface of the adjacent portion of said bowl-shaped member. 75

3. A lighting fixture comprising a bowl-shaped member of translucent material, which member is provided with a central opening, and the inner surface of which bowl-shaped member curves gradually outwardly and upwardly from a point adjacent the edge of said opening, a light source, and a bulb surrounding the same, the outer surface of the lower end portion of which is provided with a metal coating, the upper 80 edge of which is located in a plane in substantially flush relation to the adjacent inner surface of the said bowl-shaped member.

4. A lighting fixture comprising a bowl-shaped member of translucent material having a central opening, means for supporting said member, a bulb having a filament located therein which is adapted to be rendered incandescent by the passage of an electric current therethrough, and the said bulb also having upon the outer surface of its lower end portion a coating of metal the inner surface of which is light reflecting, the upper edge of said coating being located in a plane above the plane in which the said 100 filament is located, and means for supporting the said bulb with its lower end portion projecting into the said opening to such position that the upper edge of said coating is in substantially flush relation with respect to the adjacent inner surface of the said bowl-shaped member. 105

5. A lighting fixture comprising a bowl-shaped member of translucent material, said member being provided with an opening therethrough, means for supporting said bowl-shaped member, a bulb having a source of light therein, the outer surface of the lower portion of said bulb being provided with a coating, the interior surface of which is light reflecting, the upper edge of which is located in a plane above that in which the light source is located, means for supporting the said bulb with its lower end 110 projecting into the said opening, and means for diffusing the rays of light which radiate 115 from the said light source. 120

6. A lighting fixture comprising a bowl-shaped member of translucent material having an opening therethrough, means for supporting said bowl, a glass bulb having a filament therein which is adapted to be rendered incandescent by the flow of electric current therethrough, a metal coating upon the outer surface of the lower end portion 125 130

- of the said bulb, the upper edge of which is located within a plane above the said filament, means for supporting the said bulb with its lower end projecting into the said 5 opening to a position such that the upper edge of said coating occupies a plane substantially coincident with the plane of the adjacent portion of the inner surface of said bowl-shaped member, and a diffusing shield 10 surrounding the said bulb with its lower edge located in such relation to the upper edge of the said coating that the rays of light which radiate from the said filament must impinge upon said shield before they 15 impinge upon the ceiling of a room or other structure in which the fixture may be located or upon the inner surface of said bowl-shaped member.
7. A lighting fixture comprising a bowl-shaped member of translucent material having a central opening therethrough, the upper edge of which is surrounded by an upwardly extending rim, an electric light bulb 20 projecting through the said opening, the lower portion of said bulb being provided 25 with a light reflecting coating the upper
- edge of which is located in a plane coincident with the plane of the upper surface of said bowl surrounding said rim and below the upper edge of the said rim, and a 30 light source located within said bulb below the upper edge of the said coating.
8. A lighting fixture comprising a shade of translucent material of bowl-shape having a central opening therethrough, provided with a rim around its upper edge, an electric light bulb provided with a filament which is adapted to be rendered incandescent, and also provided upon the outer surface of its lower end portion with a light 35 reflecting coating the upper edge of which extends a short distance above the said filament and occupies a plane a distance below the upper edge of the said rim, and a light diffusing means through which the rays 40 which extend upwardly from the said filament pass, substantially as described.

In testimony that I claim the foregoing as my invention I have hereunto signed my name this 19th day of November, 1924.

CLARENCE ERROL FERREE.
